Patented Dec. 15, 1914.

THE NORRIS PETERS CO., PHOTO-LITHO., WASHINGTON, D. C.

UNITED STATES PATENT OFFICE.

GEORGE W. FRY, OF EAGLE, IDAHO.

THILL-SUPPORT.

1,121,344.

Specification of Letters Patent. Patented Dec. 15, 1914.

Application filed November 20, 1912. Serial No. 732,573.

To all whom it may concern:

Be it known that I, GEORGE W. FRY, a citizen of the United States, residing at Eagle, in the county of Ada and State of Idaho, have invented certain new and useful Improvements in Thill-Supports, of which the following is a specification.

This invention relates to thill supports for a harness and it consists of the novel features hereinafter described and claimed.

An object of the invention is to provide a support adapted to be connected with the back strap of a harness and which is designed to effectually hold a thill in proper position with relation to the side of the animal to which the harness is applied. In conjunction with the said support, means is provided which is applied to the thill for preventing the said support from moving rearwardly along the thill beyond a certain point. The breeching strap of the harness is adapted to be connected with the support, and consequently, when rearward strain is applied to the breeching strap, the thill support exerts a rearward thrust directly along the thill. Also means is provided for connecting the belly band with the said thill support, whereby the support is held in proper position with relation to the side of the animal.

The thill support comprises a crook-shaped member to which is attached a resilient thill retainer member. The retaining member is under tension with a tendency to normally engage the end of the crook-shaped member, and when pressure is applied to the side of the resilient member, a sufficient space is opened to permit the thill to be swung or moved vertically out of engagement with the support.

With these and other objects in view, the invention consists in certain novel features of construction as hereinafter shown and described, and then particularly pointed out in the claim and in the drawings illustrative of the preferred embodiment of the invention.

In the accompanying drawing, Figure 1 is a perspective view of the thill support. Fig. 2 is an edge elevation of the same showing the thill in section. Fig. 3 is an edge elevation of the support with parts in section showing the thill about to be seated in the support. Fig. 4 is an elevation of the inner side of the support.

Corresponding and like parts are re-

ferred to in the following description and indicated in all the views of the accompanying drawing by the same reference characters.

The thill support includes a crook-shaped member 1 which is provided with a shank 2 and a bill 3. The shank 2 is provided in the vicinity of its upper end with an opening 4 through which a billet or strap 5 may be passed, and the back strap of the harness (not shown) may be connected with the billet 5 in any suitable manner. Ears 6 are formed at the side edges of the lower portion of the shank 2 of the member 1 and are adapted to be bent back over a billet 7 to which the belly band (not shown) of the harness may be connected in any suitable manner. As an additional securing means a rivet 8 may be passed through the billet 7 and the shank 2.

A retaining member 9 is secured to the upper part of the shank 2 by means of a rivet 10. The said member 9 is preferably formed from resilient sheet metal and the said member 9 is provided with a portion 11 which is disposed at an angle to the shank 2, and which normally bears at its lower end against the inner side of the bill 3. Flanges 12 are provided at the side edges 85 of the portion 11 and normally bridge the space between the shank 2 and the bill 3. The said flanges are provided at their lower ends with curved edges 13 which are adapted to lie over the upper side of the thill 90 when the same is in position in the support. The member 1 is provided at its rear edge with a tongue 14 which in turn is provided with an opening 15 through which the breeching strap 16 is adapted to be passed. 95

The thill indicated at 17 is provided at its side with a plate 18 which in turn is provided at its rear end with a lug 19. The lug 19 is adapted to engage the edge of the member 1 when backward pull is exerted 100 upon the breeching strap 16, and thus the said lug prevents the member 1 from moving rearwardly along the thill 17 beyond a certain point.

When the thill support is applied to a set 105 of harness, the bill 3 is upwardly disposed. Therefore it will be seen that the thill 17 may be lowered or swung down, and when the thill encounters the portion 11 of the member 9, the said portion 11 together with the flanges 12, are flexed inwardly, and the thill 17 may enter the lower portion of the

crook-shaped member 1. After this has been done the resiliency of the member 9 will cause the portion 11 and the flanges 12 to move in an outward direction to their normal positions and the upper portion of the thill is received below the curved edges 13 of the flanges 12. The thill 17 may then be moved longitudinally until the lug 19 encounters the edge of the member 1. The plate 18 not only serves as a wear plate between the thill 17 and the member 1, but it also serves as a shield for the thill 17 when it strikes the inclined portion 11 of the member 9. In order to remove the thill 17 from the support, the portion 11 of the member 9 is pushed in an inward direction when the space between the shank 2 and the bill 3 of the member 1 is cleared and the thill 17 may be readily lifted out of engagement with the support.

I claim:

A thill support comprising a member having a shank portion and a hook, and a

resilient member mounted upon the shank and having a free end portion which normally engages the bill of the hook and the outer side of the thill when said thill is in normally harnessed position, said member having at its free end portion spaced, rearwardly extending side flanges between which the aforesaid shank is located, and said flanges normally bridging the space between the shank and the bill of the hook, the outer ends of the lower edges of the flanges being more remote from the point of attachment of the resilient member to the shank than the inner ends of the lower edges of the said flanges to said point of attachment.

In testimony whereof I affix my signature in presence of two witnesses.

GEORGE W. FRY.
